UNITED STATES PATENT OFFICE.

JOHN J. MENDENHALL, OF CLEAREWATER, FLORIDA.

ADJUSTABLE SWEAT-BAND BACKING.

1,219,755.

Specification of Letters Patent. Patented Mar. 20, 1917.

Application filed August 16, 1916. Serial No. 115,294.

To all whom it may concern:

Be it known that I, JOHN J. MENDENHALL, a citizen of the United States, and a resident of Clearwater, in the county of Pinellas and State of Florida, have invented a certain new and useful Improvement in Adjustable Sweat-Band Backings, of which the following is a specification.

My present invention relates to adjustable sweat band backings for use in connection with head coverings, such as hats, caps, helmets, etc.

The principal object of my invention is to provide devices of the character described which will effectively prevent baldness, which usually results from compressing the blood vessels, by use of the hat, and starving the roots of the hair. This I accomplish by bringing pressure upon the heads 20 of the wearers only at those portions remote from the arteries, veins, and the lymphatics, which supply and nourish the hair, sufficient to retain the head covering against casual displacement.

Other objects of my invention are to provide devices of the character described which are simple in construction and inexpensive to manufacture; capable of adjustment to the requirements of the individual 30 wearing them; and, devices which are compact and which do not render the head covering cumbersome because of the use of accessories of this character.

Further objects of my invention will appear in the following detailed description, taken in connection with the accompanying drawing, forming a part of this specification, and in which drawing:—

Figure 1 is a central longitudinal sectional view through a head covering equipped with a device constructed according to my invention, the head covering being shown in engagement with the head of an individual.

Fig. 2 is a perspective view of a device constructed according to my invention.

Fig. 3 is a central longitudinal sectional view, on an enlarged scale, through a shaper and its carrier, forming a part of the device.

The main vessels carrying nourishment to the roots of the hair on top of the head and carrying waste matter away are in front of the ears, as indicated by the black square 55 4 in Fig. 1 of the drawing, on the under side of the skin, and are easily compressed

between the skin and the bony structure of the skull. Two other groups of vessels are in the forehead, on either side of the median line, as indicated at 5 by the black square, 60 these vessels supplying the hair above the forehead. Two other groups supply the back part of the head, and are on each side of the median line as indicated at 6, by black square in Fig. 1. The ordinary hat 65 affects the growth of hair by compressing the arteries, the veins, the lymphatics, and to some extent the nerves that supply and nourish the hair, the sweat band compressing the vessels and starving the roots of the 70 hair.

In the drawing, where like characters designate like parts, A designates a head covering, such as a hat, including a crown B and a sweat band C; and D, backing device for 75 sweat band C including a flexible band or carrier E, and shapers F adjustably carried by band E.

While I have herein shown the invention as applied to a hat, it is to be understood 80 that it is applicable to all types of head coverings which are retained against casual displacement by bringing pressure upon the head at the sweat band.

Referring first to the flexible carrier or 85 band E, it may be made of any suitable material, preferably relatively light silk ribbon, which is durable and may be doubled up, if desired, with several plies upon each other in juxtaposed relation so that 90 the band, when made endless, may be of maximum size and when applied to the smaller size head coverings, the band may be doubled up to fit nicely between the sweat band C and crown B.

As to the shapers F, they are preferably made of strips of inherently stiff material, such as aluminum, which is bendable, and each shaper is primarily arcuated longitudinally so as to conform to the curvature of 100 the crown B. As suitable means for adjustably supporting said shapers from the carrier E, each shaper may be provided with a plurality of transverse slots, preferably two adjacent the end portions, the flexible 105 carrier E being trained through the first slot adjacent one end and from one face of the shaper, to the other face, then trained through the next adjacent transverse slot to the convex face of the shaper and thereafter trained through the slots of the other end of the shaper in a similar manner, as

is clearly shown in Figs. 2 and 3 of the drawing.
It is preferred, in the manufacture of the shapers to stamp the same from sheet metal, such as aluminum so that the walls of the slots 7 are at right angles to the plane of the shaper as clearly shown in Fig. 3 of the drawing, presenting rather sharp edges 8 about which the flexible carrier E is trained. This formation is not only inexpensive to manufacture, but prevents casual displacement of the shapers with respect to the flexible carrier, once they have been positioned according to the requirement of the individual using the device.

The operation of the device is as follows: No two heads are shaped exactly alike. Some heads bulge out in front of the ears where the head covering, as is now in common use, frequently cuts off the supply of nourishment to the roots of the hair. Some foreheads are full in the median line and rounded toward the sides, which permits pressure on the frontal vessels and starves out the hair on the front of the head, since the sweat band tightly engages the head at approximately the points indicated by character 5. Other heads are lacking in a protuberance on the back of the head so that the head covering fits tightly at the points marked by character 6, resulting in baldness that is low in the back of the head. If the head is free from corners and protuberances and is so round that the head covering fits tightly all around the head, baldness is most complete. When bringing a device constructed according to my invention into use, the shapers F are adjusted so that they engage the head remote from the arteries, veins, lymphatics, etc., which supply and nourish the hair.

Baldness usually begins at the summit of the crown, of the head toward the back part, at the distant and weakest part of the vessels furnishing the circulation. In such cases, the pressure has been on the vessels on the side of the head, which are perhaps the most important, and an individual can

quickly determine where the shapers should be placed in order to bring sufficient pressure upon the head to maintain the head covering against casual displacement, yet avoid pressure upon the important arteries, veins, etc.

Changes in details may be made without departing from the spirit or scope of my invention; but,

I claim:—

1. A sweat band backing comprising in combination, a band of flexible material, and a plurality of shapers of inherently stiff material permanently mounted on and adjustable longitudinally of said band.

2. A sweat band backing comprising in combination, a band of flexible material, and a plurality of arcuate strips of inherently stiff material slidably mounted on and adjustable longitudinally of said band.

3. A sweat band backing comprising in combination, a band of flexible material adapted to be inserted between the crown and the sweatband of a hat, and a plurality of arcuate strips of inherently stiff bendable material adjustable longitudinally of said band.

4. A sweat band backing comprising in combination, a band of flexible material, and a plurality of arcuate strips of inherently stiff material provided with transverse slots through which said flexible band is trained.

5. A head spacing attachment for hats comprising the following elements in combination and permanently connected together to provide a unitary device; namely, an endless band adapted for insertion between the crown and the sweatband of a hat, and a plurality of relatively stiff bendable strips slidably mounted on the band and adapted for adjustment into various positions upon the hat and to be bent to conform to the curvature of the different parts of the head, said band being adapted to frictionally hold said strips in adjusted position.

JOHN J. MENDENHALL.
